UNITED STATES PATENT OFFICE.

GEORGE KOLLSTEDE, OF PROVIDENCE, RHODE ISLAND, ASSIGNOR TO V. E. BLACK COMPANY INCORPORATED, A CORPORATION OF RHODE ISLAND.

CUFF BUTTON.

Application filed June 6, 1922. Serial No. 566,253.

To all whom it may concern:

Be it known that I, GEORGE KOLLSTEDE, a citizen of the United States, residing at Providence, in the county of Providence and State of Rhode Island, have invented certain new and useful Improvements in Cuff Buttons, of which the following is a specification.

My invention relates to cuff buttons and has for its essential objects the avoidance of open ends and the use of solder, and the attainment of these ends in an inexpensive, easily assemblable, and operable structure.

My invention consists in such parts and in such combinations of parts as fall within the scope of the appended claim.

In the accompanying drawings which form a part of this specification.

Figure 1 is a side elevation of a cuff button embodying my invention.

Figure 2, a section on line 2—2 of Figure 1,

Figure 3, an enlarged side elevation of one end of the button, partially in section on line 3—3 of Figure 2,

Figure 4, a detail side elevation of the link member, and

Figure 5, a like elevation of the same before attachment.

Like reference characters indicate like parts throughout the views.

The button comprises two heads 7 alike in every detail, and a description of one will serve for both. Each head comprises a lining plate 8, preferably convexo-concave, and in the present instance of polygonal outline, provided upon its rear with a peripheral groove 9. Upon its rear or concave face there is cut and formed therefrom integral cylindrical housings comprising hollow sides 11 with integral closure portions 12 at their outer ends. Their inner ends are open as at 13. The housings are in diametrical alignment with each other on opposite sides of the center of the plate. Fast to each lining plate is a face or ornamental plate comprising a convexo-concave body portion

15 covering the face of the lining plate, also a rearwardly extending flange 17 embracing the periphery of the latter plate, and provided with a peripheral bead or rolled over portion 18 seated in the groove 9.

The link member represented in general way by 20 comprises a central or body portion 21 provided at each end with a pair of curved 55 diverging arms 23 and 24, the former preferably longer than the latter. Upon the ends of the arms 23 and 24 are fingers 25 and 26 respectively, and at right angles to the fingers at their ends are trunnions 27 and 28 60 respectively. The member 20 is of pliable metal to permit the arms 23 and 24 to be bent either towards or away from each other, and remain set in whichever position they are placed. This yielding character of the arms 65 is utilized in assembling the parts. Initially the arms are close together, as shown in Fig. 5, and are then manually expanded to the positions shown in Figure 4 so that the trunnions 27 and 28 enter the open ends 13 of 70 the housings and are pivotally seated therein, with the fingers 25 and 26 in contact with the inner ends of the body portions 11 of the housings or bearings. The heads 7 have free pivotal movement relatively to the 75 link member 20.

I claim:

In a cuff-button, heads comprising lining plates provided with peripheral grooves, face plates embracing the lining plates, beads on 80 the face plates seated in the grooves, horizontally disposed housings integral with the lining plates provided with open inner ends, and a link member comprising a body portion, pairs of pliable diverging arms integral 85 with the ends of the body portion, fingers upon the ends of the arms, and trunnions on the fingers at right angles to the fingers extending into the open ends of the housings.

In testimony whereof I have affixed my signature.

GEORGE KOLLSTEDE.
